Inventor:

J. C. Richardson
by
Messrs. Knueck & Lawrence

United States Patent Office.

J. C. RICHARDSON, OF ILION, NEW YORK.

Letters Patent No. 91,367, dated June 15, 1869.

IMPROVED FORK-BLANK.

The Schedule referred to in these Letters Patent and making part of the same.

To all whom it may concern:

Be it known that I, J. C. RICHARDSON, of Ilion, in the county of Herkimer, and State of New York, have invented a new and improved Fork-Blank; and I do hereby declare that the following is a full, clear, and exact description thereof, reference being had to the accompanying drawings, making a part of this specification, in which—

Figure 1 is a perspective view of a narrow strip of metal from which the blanks are produced.

Figure 2 is a perspective view of a tool which is adapted for perforating the blanks, to form their shoulders, preparatory to splitting the metal.

Figure 3 shows the general form of two blanks which have been perforated, but not split.

Figures 4 and 5 show blanks which have been perforated and split.

Figure 6 shows a blank ready to be formed into a fork.

Similar letters of reference indicate corresponding parts in the several figures.

This invention relates to an improvement in the manufacture of blanks from which to produce dung or stable-forks.

The object of my invention is to produce the shoulder or crotch between the middle tines of a fork-blank by crowding the metal which is displaced to form such shoulder or opening into the body of metal at the junction of the head and shank or tang of the blank, thereby greatly strengthening the metal at the point which is subjected to the greatest strain in using a fork, and avoiding the necessity of cutting out a piece of the stock, to produce said shoulder, preparatory to spreading and shaping the prongs of the blank, as will be hereinafter explained.

To enable others skilled in the art to understand my invention, I will describe its construction and operation.

In the accompanying drawings—

A represents a strip of metal, which is made of the proper width and thickness to produce four-tined fork-blanks, such as are shown in figs. 3, 4, 5, and 6.

By means of a suitable cutter, I form, at one operation, the tang or shank B and rounded or bevelled head c. At the same time, I separate a blank from the stock, and leave the end of the strip A, from which the blank was cut, of the exact shape required for the ends of the prongs, C C', of the succeeding blank; and the space which is left in the middle of the width of the strip A, by cutting out the tang or shank B, allows the prongs C C' to be separated, preparatory to drawing them out into finished tines.

Previous to splitting the blanks, as shown at h g in figs. 4, 5, and 6, I produce what are termed the shoulders on the blanks. To do this, I form, through each

blank, at the point a, a hole, which will vary in width, according to the size of the fork to be produced, or the distance apart required for the middle tines of a fork.

This space or hole a has been made heretofore by cutting a piece of the metal from the blank; also by leaving the piece cut out upon the end of the tang or shank of a succeeding blank. In the former instance, the piece is wasted, and the shoulder necessarily reduced in thickness. In the latter instance, the end of the tang or shank upon which said piece is left requires to be hammered and reduced to a finished point.

I now produce the hole a, of any required size and shape, by means of a tapering tool, substantially as shown in fig. 2, and lettered G, by means of which, and while the blank is in a highly-heated state, the metal which is displaced, to produce the hole a, is crowded out laterally, and condensed into the body of metal which is at the junction of the head c and tang or shank B.

After thus producing the openings a, the blanks are split, as shown at h g, so that the prongs C C C' can be spread out, and drawn down, to form a fork, in the usual well-known manner.

I prefer to construct the blanks of the form substantially as shown in the drawing, fig. 5; that is to say, with a tang or shank, B, and a rounded shoulder, c, produced by cutting from a plate, A, substantially as above described; but I do not confine my invention to this mode of giving shape to the fork-blank, as the head c and tang B can be produced by hammering and drawing, or in any other suitable manner, either previous to or succeeding the operation of forming the hole a, by crowding the displaced metal into the head of the blank.

I do not claim, under this patent, the forming of a shoulder upon a fork-blank, by cutting out a piece of metal therefrom, as this has been done before.

What I claim as my invention, and desire to secure by Letters Patent, is—

1. In the manufacture of a fork-blank, substantially such as described, crowding the metal which occupied the space a into that part of the blank constituting the head, in the manner specified, so as to condense the metal of said head, and thereby strengthen the shoulder at its junction with the tang B, all substantially as described.

2. The improved new article of manufacture herein described, to wit, the fork-blank, with the metal which occupied the space a forced into the head of the blank, at the junction of the head with the tang B, all as set forth.

Witnesses:
